HUBERT McL. ARMISTEAD, OF SAN FRANCISCO, CALIFORNIA, ASSIGNOR TO MANIFOLD IMPRESSIONS CORPORATION, OF CARSON CITY, NEVADA, A CORPORATION OF NEVADA.

TYPEWRITER AND THE LIKE.

Application filed August 6, 1925. Serial No. 48,580.

This invention relates to improvements in typewriters and similar type impression devices, and more particularly has to do with an improved platen for such devices.

As is well known in the operation of typewriters and the like, noise results from the striking of the type against the platen, and it has heretofore been proposed to deaden the sound of the blows of the type upon the platen by employing a sound deadening covering over the outer face thereof. Aside from noise due to this cause, however, in the operation of type writing machines and the like, I have found that considerable of the noise results from the transmission to and registration upon the platen of sounds and noises arising from other operating parts or mechanism of the machine.

An object of the present invention is to eliminate or prevent noise in the operation of typewriting machines and the like; to provide for the elimination, absorption or deadening not only sound vibrations caused by the blows of the type upon the platen, but also to prevent sound and noise that arises by interaction, interfusion, intercommunication, echo or reverberations from other associated operating mechanism of the machine, from being conveyed to and registered upon the platen as well as to prevent such noises being disseminated back through the parts of the machine.

Another object of the invention is to provide an improved platen possessing the characteristics referred to and which at the same time will afford the maximum of efficient type impact area as regards the length thereof.

A further object of the invention is to provide an improved platen constructed and arranged to accomplish the purposes mentioned, and which will be of a simple, practical, serviceable and inexpensive nature.

The invention, with other objects and advantages thereof, and the particular construction, combinations and arrangements of parts comprising the same, will be understood from the hereinafter contained detail description when considered in connection with the accompanying drawings, forming part hereof and illustrating one embodiment of the invention.

In the drawings:

Figure 1 is a top plan view of a portion of a typewriting machine equipped with a

platen constructed in accordance with the present invention.

Fig. 2 is a longitudinal section of the platen with parts shown in elevation.

Fig. 3 is a longitudinal section of the platen, with certain of the parts removed. 60

Fig. 4 is a transverse section on the line 4-4 of Fig. 2.

Fig. 5 is a detail perspective of one of the end heads of the platen.

Fig. 6 is a detail perspective of an end portion of the main outer shell member of the platen. 65

Fig. 7 is a detail section of one of the sound insulating members prior to its introduction between one of the end heads and one end portion of the platen. 70

Fig. 8 is a detail longitudinal section of the sound insulating member illustrated Fig. 7, after its introduction in place between one of the end heads and the main shell member 75 of the platen.

Fig. 9 is an elevation of a section of the insulating means between the main shell member of the platen and the outer impact thereof. 80

The invention comprehends an improved platen including a type impact member and supporting means therefor, said platen having means for preventing or absorbing or deadening sound vibrations caused by the impact of the type against its impact member and being so constructed as to be entirely free from sound conducting parts in contact. 85

While a specific embodiment of the invention is illustrated in the drawings, it will of course be understood that changes and obvious modifications may be made in the particular construction of platen shown, and the invention embodied in other forms and applied to the various kinds of analogous type impression machines, as will appeal to those skilled in the art and falling within the scope of the appended claims, without departing from the spirit of the invention. 95

In Figure 1 of the drawings is shown, in a general way, a conventional form of typewriter provided with a platen constructed in accordance with the present invention, only such portion of the typewriter structure being illustrated as will be sufficient to a clear 100 understanding of the application thereto of my improved platen. 1 designates the main frame of the machine, 2 the keys, 3 the ink- 105

ing ribbon, 4 the ribbon spools, 6 the index pointer and 5 the paper guide apron, the improved platen being designated as a whole, in this view, by the numeral 7.

As hereinbefore stated platens constructed in accordance with the present invention have a wide range of usefulness, the invention being applicable to various forms and classes of typewriters and like type impression machines. The particular exemplification of the invention illustrated in the drawings is particularly adapted for manifolding platens for typewriters of the type disclosed in Patents Nos. 1,467,532 and 1,502,178 dated September 11, 1923 and July 22, 1924, respectively, and my application filed May 26, 1925, Serial No. 32,904, and in which, the platen has intimately incorporated therewith a plurality of pairs of auxiliary ribbon carrying arms adapted to be swung to carry their ribbons down to a line of impact in front of the platen, and moved upwardly to a position above and rearwardly of the platen.

Referring to a detail description of the particular embodiment of the invention illustrated in the drawings, and reference being had particularly to Figures 2, 3, and 4 thereof, 8 designates the central supporting and operating shaft of the platen rotatably and linearly slidably mounted in journals 9 on end frame members 10 of a platen carriage, said shaft having at either end turning knobs 11. Shouldered between the opposing inner ends of the journals 9 are fixed casings 12, which are connected by a tubular member 13. Mounted for independent rotation about the platen shaft 8 within the tubular member 13 is an assemblage of nested sleeves 14, the end of said sleeves projecting into the casings 12, and each having a crank arm 15 provided with a tail piece 16, each of the tail pieces being provided with a stud 17 which plays in and through a slot 18 in a chamber 19 of one of the casings 12. Upon the platen shaft 8 is mounted for independent rotation a prime operating member in the form of a sleeve 20, having an operating knob 21 at one end. The other end of the sleeve 20 extends into the chamber 19 and has fingers 22 adapted to act upon the studs 17 and turn the crank arms 15, which in turn move the pairs of ribbon carrying arms 23. The ribbon carrying arms 23 are pivotally mounted at their inner ends at 24 to and within the casings 12, the latter being provided with peripheral guide slots 25 through which are entered said arms. The ribbon carrying arms 23 are each provided with a slot 26 and are slidably connected with the crank arms 15 by pins 27 on the crank arms 15 engaging said slots.

At the ends of the platen 7 in Figure 2 of the drawings, is illustrated mechanism providing for the rotation of the platen by the shaft 8; detail mechanism for the con-

trol of the platen rotation for definite and variable line spacing; and for the selective operation of the crank arms 15. The mechanism referred to is the same as that described in detail in Patent No. 1,502,178, and my application Serial No. 32,904, and a repetition of the detailed description of said parts and mechanism in this application is not necessary to a complete understanding of the present invention.

Referring now to Figure 3 of the drawings, the platen proper comprises a tubular impact member and end heads 27, which are constructed of metal or other suitable material, the platen being mounted for rotation by having its end heads 27 journaled upon flanges 28 of the fixed casings 12. The tubular impact member is made up of a foundation or main tubular member or shell 29 constructed of metal or other suitable material, a sound deadening or insulating covering or cylinder 30 of felt upon the outer face of the main tubular member 29, and an outer covering or sheath 31 of rubber constituting the working face of the platen, the intermediate sound deadening or covering 30 completely separating and forming efficient sound deadening means between the outer rubber covering 31 and the main tubular member 29. The sound deadening or insulating covering 30 and the outer covering or sheath 31, which, as will be understood, are tightly secured one upon the other upon the outer face of the main tubular member 29, may be formed and secured upon the outer face of the main tubular member 29 in any suitable way. In the particular construction shown, see Figure 9 of the drawings, the intermediate sound deadening covering or cylinder 30 is formed by a strip of felt wound spirally upon the main tubular member 29, and the main tubular member 29 is provided with a roughened outer face 32 by scoring or the like to assist in securing the felt covering 30 in place.

The end heads 27 of the platen each comprise an outer peripheral portion 33, a radially extending portion 34, and an inner portion 35, the inner portion 35 of the end head 27 located at the left end of the platen extending inwardly while the end portion 35 of the other end head is coextensive with its outer peripheral portion 33, said inner portions 35 of the end heads 27 rotatably engaging the flanges 28 of the fixed casings 12.

Means is provided for completely separating the supporting end heads 27 of the platen from its impact member by a sound deadening or insulating medium while at the same time connecting the impact member to the end heads 27 for rotation therewith. The means for this purpose comprises sound deadening or insulating collars or ring members of felt or other sound insulating material suitable for the purpose, the insulating collars or like

members each having a peripheral portion 37 and a radially extending portion 38. The main tubular member 29 of the type impact member, at either end, is provided with an 5 interior annular recess 39, said recesses having the peripheral wall portions 40 and end wall portions or shoulders 41. The walls 40 and 41 of the recesses 39, and the peripheral portions 33 of the end heads 27 are provided 10 with roughened outer faces by scoring or the like, as shown. The exterior diameter of the end heads 27 is less than the interior diameter of the annular recesses 39 of the main tubular member 29, and the parts are assembled, as 15 shown, with the peripheral portions 37 of the insulating collars or like members in tight interfitting engagement with and between the roughened outer faces of the peripheral portions 33 of the end heads 27 and the end portions 20 of the main tubular member 29, the radially extending portions 33 of the end heads 27 being pressed against the radially extending portions 37 of the insulating collars or ring members, and the latter pressed 25 against the roughened faces of the end walls 40 and shoulders 41 of the recesses 39, the construction and arrangement of parts being such that the sound insulating collars or ring members completely separate the end heads 30 from contact with the main tubular member 29, and these parts are coupled to rotate together. The supporting end head 27 at the left of the platen has an internal gear 42 fixed thereto, rotary movement being transmitted to the platen through the countershaft 43 and the pinion 44 meshing with the internal gear 42 on said end head.

In practicing the invention the insulating collars or ring members may be constructed 40 in flat washer like form as illustrated Figure 7 of the drawings, and the parts assembled by placing the insulating collars or ring members 37, 38, in this flat formation, against the inner side of the end heads 27 and then 45 forcing the end heads 27 and the insulating collars 37, 38 home within the ends of the main tubular member 29, the collars 37, 38 being pressed into the recesses 39 in tight fitting engagement with the walls and shoulders 50 thereof and with the end heads 27.

The platen is provided with sound deadening or insulating means completely filling the space between the tubular member or sleeve 13, the inner sides of the end heads 27 and the main tubular member 29 of the platen. This sound deadening filling is shown as consisting of a plurality of rings or centrally apertured cylindrical sections 46 of felt or the like arranged end to end in close formation, as shown, said rings or cylindrical sections fitting closely about and slidably engaging the sleeve 13.

While the sound insulating or deadening means of the platen has been specifically referred to as formed of felt, it will be under-

stood that said insulating means including the insulating covering 30, the sound deadening or insulating filling 46, and the insulating collars or ring members 37, 38, may be constructed of any other suitable or equivalent material having similar sound insulating or deadening qualities, for instance, Java floss, among other insulating materials that may be employed instead of felt.

It will be noted that by the invention an improved platen is provided which is entirely free from sound conducting parts in contact; that the invention provides for the complete elimination of continuity of sound conducting elements between the type impact member of the platen and its supporting means, and that the improved structure provides for the elimination of not only sound vibrations caused by the impact of the type against the working face of the platen but also for preventing transmission of sound by conduction from the platen to other parts of the machine, and from other parts of the machine to the platen, at the same time the improved construction affords the fullest extent of type impact area for its length, permitting the use of the total length of platen, including the width of the supporting end heads, and is of a practical, efficient, serviceable, inexpensive nature.

What I claim is:

1. In a platen for typewriters and the like, and in combination, an outer type impact member, a separate rigid hollow shell or core member and end supports, members composed of sound insulating material interposed between and automatically connecting the rigid shell or core members and end supports for rotation together, and a shaft extending through and beyond the shell or core member for engagement with associated typewriter mechanism, and a sound insulating or non-conducting medium arranged within the shell or core member to prevent the echo or reverberation of sound or noise occurring within the shell or core member from being transmitted to the shell or core member.

2. In a platen for typewriters and the like, a type impact member, rotatable end supports for the type impact member, and sound insulating or non-conducting means separating the type impact member from contact and sound conduction with the rotatable end supports, and interfitting therewith to automatically connect the same for rotation together.

3. In a platen for typewriters or the like, a single tubular type impact member, rotatable end supports for the platen comprising members having outer annular peripheral portions adapted to be arranged within the ends of the platen, and members of sound insulating or non-conducting material separating the peripheral portions of the end supports from contact with the impact member and wholly tightly automatically interfitting.

therewith to constitute permanent means for connecting the same for rotation together.

4. In a platen for typewriters or the like, a tubular member having at its ends interior roughened face portions, rotatable end supports for the platen having annular peripheral portions adapted to be arranged within the ends of the tubular member and provided with outer roughened faces, and annular members of sound insulating or non-conducting material tightly fitting between the roughened end face portions of the tubular member and the roughened face of the annular peripheral portions of the rotatable end supports, said annular members separating the tubular member from contact with the end supports and constituting means connecting the same for rotation together.

5. In typewriters and similar motion transmitting mechanisms, a coupling comprising a rotatable member having a recess extending inwardly from one end thereof, the wall of said recess having a roughened face portion, a rotatable coacting member having an annular peripheral portion adapted to be arranged within the recess of the first mentioned member in spaced relation with the walls of the recess and provided with an outer roughened face, and an annular member of sound insulating or non-conducting material tightly fitting between the roughened face portion of the wall of said recess and the roughened face of said annular peripheral portion, said annular member separating the said members from contact and constituting means connecting the same for rotation together.

6. A platen for typewriters and the like, including a rigid hollow core member, and members extending within the ends of the core member to support the same, and sound insulating means wholly interposed between the hollow core member and the end supports, said sound insulating means separating the hollow core member and the end members from contact and sound conduction with each other, and interfitting therewith to automatically connect the same for rotation together.

7. A platen for typewriters and the like, including a rigid hollow core member, an associated end support member, one of said members extending within the other to support the same, and sound insulating means wholly interposed between the hollow core member and the end support, said sound insulating means separating the hollow core

member and the end support from contact and sound conduction with each other, and interfitting therewith to automatically connect the same for rotation together.

8. In a platen for typewriters and the like, including a type impact member, a single inner shell or core member, and end supports, a sound insulating medium wholly separating the outer type impact member and the rigid inner shell from sound conduction with each other, and members composed solely of a sound insulating or non-conducting element completely separating the inner shell and end supports from sound conduction with each other and automatically connecting the same for permanent rotation together.

9. In a typewriting machine or the like, a platen including a type impact member, a rotatable support therefor, sound insulating or non-conducting means completely separating the type impact member and the rotatable support from sound conduction with each other and wholly interfitting automatically therewith to constitute permanent means for connecting the same together, and associated mechanism including means for rotating the platen connected with the rotatable support of the platen.

10. In a platen for typewriters and the like, a type impact member, rotatable end supports for the type impact member, and annular members of felt separating the type impact member from contact and sound conduction with the rotatable end supports and interfitting therewith to automatically connect the same for rotation together, said annular members constituting the sole means of connection between the type impact member and the end supports.

11. In a platen for typewriters and the like, a type impact member, rotatable end supporting member therefor, one of said members extending within the other, said members being adapted for contractual coherence and concentric rotation, and a sound insulating element interposed between and of a character for contractual coherence with and to exert permanent intermediate pressure on said members, said pressural coherency constituting automatic means providing for permanent concentric rotation of said members.

In testimony whereof I hereunto affix my signature.

HUBERT McL. ARMISTEAD.
